U.S. Appl. No. 15/865,981 Non-Final Office Action dated Mar. 8, 2018.

Primary Examiner — Cathron C Brooks

(74) *Attorney, Agent, or Firm* — K&L Gates LLP

CLAIM

The ornamental design for a recessed lighting fixture with independent adjustment between a light assembly and a driver assembly, as shown and described herein.

DESCRIPTION

FIG. 1 illustrates a perspective view of a recessed lighting fixture.

FIG. 2 illustrates a left-side view of the recessed lighting fixture.

FIG. 3 illustrates a right-side view of the recessed lighting fixture.

FIG. 4 illustrates a front view of the recessed lighting fixture.

FIG. 5 illustrates a rear view of the recessed lighting fixture.

FIG. 6 illustrates a top-plan view of the recessed lighting fixture; and,

FIG. 7 illustrates a bottom-up view of the recessed lighting fixture.

In the drawings, the broken lines depict environmental subject matter only and form no part of the claimed design.
